UNITED STATES PATENT OFFICE.

FREDERICK JOERNS, OF ST. PAUL, MINNESOTA.

PUMP.

1,358,213.

Specification of Letters Patent.

Patented Nov. 9, 1920.

Application filed May 24, 1919. Serial No. 299,384.

To all whom it may concern:

Be it known that I, FREDERICK JOERNS, a citizen of the United States, residing at St. Paul, in the county of Ramsey and State 5 of Minnesota, have invented a new and useful Improvement in Pumps, of which the following is a specification.

This pump relates to a design which is adapted to give a constant or steady stream 10 when it is in operation and to eliminate the strain on the mechanism, which is caused in the ordinary pump construction, where it is necessary to start the water or other fluid at each stroke of the pump. The construction 15 of this pump is such that excessive wear on any one part is eliminated, due to the arrangement of the parts and the simple, inexpensive design with the parts of the same accessible, so that they can be easily put together or taken apart, together with a hood construction, which protects the operating gears, eliminating the ordinary danger from the same and covering them from exposure 20 to the weather, makes a most desirable design for a steady stream pump.

The parts of this pump are so fitted together as to give a compact design and so arranged as to overcome any excessive amount of friction, the operating levers having 25 a peculiar shape and being so connected that the pump rods are moved up and down freely with practically little or no side thrusts against the same. This is due to the peculiar shape and pivoting of 30 the operating levers, together with the connecting links, which are connected to the pump rods. The operating gears of this pump are held stationary against movement so that they can be freely rotated on their 35 axis, which remains in the same position at all times during the operation of the pump. This pump is arranged with two sets of levers and connecting arms, which connect the levers to the operating gears in such a 40 manner that both levers move upward at the same time a certain distance or number of degrees during the rotation of the operating gears, but the levers do not move downward together at any time. In this manner, 45 the pump rods can be operated so as to give a constant flowing stream of liquid from the pump with the least possible wear and friction on the pump parts.

In the drawing:

Figure 1 is a perspective view of the pump, the hood of which is removed.

Fig. 2 is a front elevation of the pump, also having the hood removed and illustrating a portion in cross section.

Fig. 3 is a side elevation, partly illustrated in cross section, of the pump.

Figs. 4 and 5 are details, partly illustrated in cross section, of a portion of the pump.

Figs. 6 and 7 are diagrammatic illustrations of some of the pump parts.

The pump A is illustrated so as to operate the ordinary, well-known construction of two plungers in one working barrel, one of the pump rods being hollow so that the other 60 rod can reciprocate therein to operate the two plungers in the barrel.

The standard or body portion 1 of the pump A is cylindrical and has a horizontal flange 2 at the base of the same, which connects with the drop pipe 3 in any suitable manner, so as to connect the water or fluid chamber 4 of the standard 1 with the same. The chamber 4 is formed with a division 75 wall 5, which forms a compression chamber 6 and an outlet passageway 7, so as to discharge the liquid from the chamber 4 through the opening 8 near the top of the standard 1.

A head portion 9 is formed on the standard 85 1 of the pump A, which has side flanges 10 and a centrally positioned, upwardly projecting flange 11, which is formed with a bearing 12 for the shaft 13. The shaft 13 is freely journaled in the bearing 12 and is 90 cut down on its ends so as to receive similar gears 14 and 15, which are held rigidly to the shaft by a key 16 and a nut 18, that is threaded to each end of the shaft, in this manner holding the gears 14 and 15 rigidly 95 to the shaft 13 and rotatable with the shaft in the bearing 12.

The gears 14 and 15 are driven by suitable pinions 19, which are mounted on the shaft 20, the shaft 20 extending through the head 9, and having suitable bearings in the side flanges 10 of the same. A suitable pulley 21 is secured to the shaft 20 in the ordinary manner, so that the shaft 20 can be driven by a belt from any suitable 105 source of power. The hub of the pulley 21 is formed with suitable teeth, which can be engaged by similar teeth formed on the handle 22 so that the shaft 20 can be rotated by hand, if it is so desired.

A link 23 is pivotally secured, on one end, at 24, to the outer surface of the gear 14,

near the periphery of the same and the other end of the link 23 is pivotally connected at 25 to the forward end of the lever arm 26. The rear end of the lever arm 26 is pivotally 5 secured to a shaft 27, which extends transversely through the head 9, below the shaft 20 and is rigidly secured in a suitable manner to the side flanges 10 of the same, so as to hold the rear end of the lever 26 on the 10 shaft 27 between one of the flanges 10 and the central flange 11.

The hollow pump rod 28 of the pump A is rigidly connected to a cross head 29, which is freely slideable on the vertically extending guide rods 30, so as to be reciprocated up and down freely and the cross head 29 is connected with the lever arm 26 by means of the connecting rod 31, which is pivoted on one end to the lever arm 26 at 20 32 and having its other end pivoted at 33 to the cross head 29. Thus, when the gear 14 is operated, the hollow pump rod 28 will be reciprocated up and down freely to operate the pump plunger, which is connected to the same and which is of ordinary construction, not being illustrated in the drawing.

A link 34, which is similar to the link 23, is pivoted on one end at 35 to the gear 15 and its other end is pivotally connected at 36 to the forward end of a lever arm 37, which is similar to the lever arm 26 and which is pivotally connected to the shaft 27 on its rear end so that the same can be moved up and down freely by the operation of the gear 15 by the connecting link 34.

The inner pump rod 38 is rigidly connected to an upper cross head 39, which is freely reciprocable on the guide rods 30 above the cross head 29 and the cross head 39 is connected by the connecting rod 40 to the lever arm 37, one end of the connecting rod 40 being pivoted at 41 to the lever arm 37 and the other end of the connecting rod being pivoted at 42 to the cross head 39. Thus when the gear 15 is operated, the connecting links, lever arm and connecting rod will operate the cross head 39 so as to reciprocate the inner pump rod 38 up and down. A suitable packing gland 43, of ordinary construction, is secured in the cross head 29 so as to give a liquid tight joint around the rod 38, which passes through the same and 55 is freely reciprocable when the pump is in operation.

In the operation of the pump A, the drive shaft 20 is rotated in a suitable manner either by the handle 22 or the pulley 21 and the pinions 19 engage the gears 14 and 15 to operate the same, simultaneously, and thus in turn operating the lever arms 26 and 37, which cause the connecting rods 31 and 40 to operate the cross heads 29 and 39 and thus operate the hollow pump rod

28 and the inner pump rod 38, simultaneously, the gears 14 and 15 operating in the direction of the arrow, illustrated in Fig. 3, and causing the pump rods to move in an upward direction during 216 degrees of the 70 rotation of the gears 14 and 15 and to move in a downward direction 144 degrees of the rotation of the gears.

The pivot points 24 and 35 of the upper ends of the connecting links 23 and 34, respectively, are positioned diametrically directly opposite each other on the respective gears 14 and 15, when the gears 14 and 15 are secured to the shaft 13, so that in the operation of the pump A, an overlap is obtained in the upward operation of the pump rods 28 and 38, to cause the same to travel together a certain distance. In this manner, a continuous, steady stream is discharged by the pump A and the jar, which jerks the connecting parts of the ordinary pump, is entirely eliminated. There is no overlap in the downward movement of the pump rods and their connecting elements, as they only travel 144 degrees from the uppermost position to the lowermost position.

The diagrammatic illustrations in Figs. 6 and 7, illustrate the gears 14 and 15 in line with each other and having the same axis as is true of their position in the pump A and these diagrammatic illustrations show the relative positions of the connecting links 23 and 34 and the operating levers 26 and 37.

In Fig. 6, the lever 26 together with the link 23 have not quite reached the uppermost position, while the lever 37 and the link 34 are in the lowermost position and from this point would be started in an upward direction, being thrown upward by 105 the link 34, which is attached to the gear 15, thus clearly illustrating that by the time the link 23 and lever 26 have reached their uppermost position, as is illustrated in the diagrammatic illustration of Fig. 7, that 110 the link 34 and the link 37 would be in the position illustrated in this figure, when the link 23 and lever 26 start in a downward direction. When the link 34 and lever 37 assume the position of the respective parts, 115 such as the link 23 and the lever 26, as illustrated in Fig. 6, then the link 23 and the lever 26 will be at their lowermost point or in the position illustrated by the respective parts in Fig. 6 by the link 34 and the lever 120 37, and before the link 34 and lever 37 start to move in a downward direction, the link 23 and lever 26 will start in an upward direction, thus causing the links 23 and 34 and the levers 26 and 37 to move in a similar 125 direction during a portion of the rotation of the gears 14 and 15, giving a sufficient overlap to cause the plungers connected to the connecting rods 28 and 38 to cause a sufficient suction in the pump cylinder to 130

keep the water flowing continuously in the same during the operation of the pump A.

It is understood that two plungers are used in the operation of the pump A, one being connected to the hollow pump rod 28 and the other to the rod 38, one above the other, in the ordinary, well-known manner, but not being illustrated in the drawing.

The downward movement of the pump rods from the uppermost position to the lowermost position is accomplished quicker than the forward movement, due to the positioning of the links 23 and 34 and the levers 26 and 37 and the operating of the gears 14 and 15 in unison, both gears being rigidly keyed to the shaft 13 and therefore when one of the pump rods, with its connecting parts, is traveling in a downward direction, it tends to transmit a certain amount of energy to the other gear, which is operating to draw its connecting rod in an upward direction, thereby equalizing the strain of the gears 14 and 15 and on the driving pinions 19 and preventing uneven wear of the same. In this manner, the load on the gears 14 and 15 and the pinions 19 is transferred or carried to each other through the shaft 13 in a most desirable way to give an even, smooth operating device and preventing backslashing on the gear teeth.

The simple arrangement of the connecting links, levers and connecting rods, together with the peculiar shape of the levers and the positioning of the gears, gives a most simple device, which is comparatively cheap to manufacture, eliminating any extreme side thrust on the pump rods during their reciprocation, due to the peculiar connection and pivoting of the connecting rods 31 and 40 and the levers 26 and 37. The mounting of the operating gears 14 and 15 on a single shaft concentric with each other, the shaft being held stationary in a suitable bearing, gives a rigid construction and allows the operating gears to rotate in unison and allows the driving pinions, such as 19, to effectively operate the gears with a small amount of power compared to the work done by the pump, as the friction of the working parts is reduced practically to a minimum.

The operating levers and gears 14 and 15 are covered by a removable hood 45, which is held by a pin 46 to the head so that it can pivot on the same and be raised up to expose the gears and operating levers, or the pin 46 can be removed to entirely remove the hood, as is illustrated in Figs. 1 and 2. This hood 45 extends over the front of the operating mechanism and the sides of the same rest on the forward edge 47 of the side flanges 10 of the head 9, so as to completely inclose the gears 14 and 15, together with the connecting parts, when the hood is in closed position. The hood 45 is easily

removed or swung back so that the working parts beneath the same can be oiled and looked after, if it is desired. It is also an essential feature that the side flanges 10 of the head 9 are cut away and of such a shape that the gears 14 and 15 can be easily removed or attached to the shaft 13 and the other operating mechanism is easily accessible, thus making it very easy to repair or look after the operating parts of the pump. It is always essential, in any pump, that the operating parts or gears be inclosed and for this reason the hood 45 is an important feature of this invention, together with the fact that the operating gears are so mounted and the levers so constructed and pivoted that they can be easily inclosed, giving a small compact device with a considerable amount of power for pumping purposes.

The pressure chamber 6 in the standard is also an essential feature and allows the pump to be operated to pump fluid under a considerable pressure for various purposes, discharging a steady stream of liquid under pressure from the pump. The pump A is comparatively silent in operation, without jar or jerk, operating smoothly with a small amount of power, the working parts being oiled in any suitable manner so that the same require very little attention and can be used for any suitable purpose, where it is desired to pump a steady stream of liquid.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims:

1. A device of the class described, including a pair of operating gears, means for rotating said gears in the same general direction in unison, an operating lever for each of said gears having a common pivot point on one end, a link connecting the free end of said operating lever with one of said gears and a link connecting the free end of the other of said levers with the other of said operating gears at a point diametrically opposite the connection of said first link and connecting rods adapted to connect said levers with plunger rods of said device, whereby when said gears are operated, said plunger rods will be reciprocated to cause a steady stream to be pumped by said device.

2. A pump, including a pair of operating gears connected concentric and adapted to operate in unison, means for rotating said gears, a lever for each of said gears having a common pivot point on one end, a link for connecting said lever with said operating

gears at points diametrically opposite each other, crossheads, guide rods for said crossheads, pump rods connected to said crossheads and connecting rods connecting said levers with said crossheads to cause said crossheads to be reciprocated up and down when said operating gears are rotated, to

give an overlapping motion, moving said crossheads in the same general direction during part of the stroke of said pump rods to discharge an uninterrupted stream of liquid from said pump for the purposes specified. 10

FREDERICK JOERNS.
